(57) **CLAIM**

The ornamental design for a pair of earmuffs for pet, as shown and described.

DESCRIPTION

FIG. 1 is a top perspective view of a pair of earmuffs for pet, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In FIG. 1, the broken lines on the earmuff interior depict portions of the pair of earmuffs for pet that form no part of the claimed design. The broken lines on the earmuff straps depict stitching that forms part of the claimed design.

1 Claim, 7 Drawing Sheets
